UNITED STATES PATENT OFFICE.

CHARLES N. DETWILER, OF TOLEDO, OHIO.

STUD-ATTACHING MEANS FOR ELECTRIC OUTLET MEMBERS.

1,344,077.

Specification of Letters Patent. Patented June 22, 1920.

Application filed March 24, 1919. Serial No. 284,790.

To all whom it may concern:

Be it known that I, CHARLES N. DETWILER, a citizen of the United States, and a resident of Toledo, in the county of Lucas and State of Ohio, have invented a certain new and useful Stud-Attaching Means for Electric Outlet Members; and I do hereby declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

This invention relates to terminal outlet boxes and plates for use in connection with electric wiring, and has for its object the provision of simple and improved means 20 for securing fixture studs thereto in an easy and rapid manner.

The invention is fully described in the following specification, and while, in its broader aspect, it is capable of embodiment 25 in numerous forms, a preferred embodiment thereof is illustrated in the accompanying drawings, in which,—

Figure 1 is a plan view of a terminal fixture member embodying the invention, with 30 a fixture stud attached thereto. Fig. 2 is a side elevation thereof, and Fig. 3 is a perspective view of the terminal member with the fixture stud removed therefrom.

Referring to the drawings, 1 designates a 35 terminal fixture member, in the present instance of plate form, which is provided with the customary "knock-outs" 2, to provide holes therein through which terminal wires or conduits may be projected, as well understood in the art. The member 1 is also provided with holes 3 through which screws or 40 nails may be projected to secure it to a wall, ceiling or other support. 4 designates the customary fixture stud having the feet 5 radiating from its base.

In carrying out my invention, I provide 50 the member 1 on its outer side and at one side of its center with a socket 6 and at the opposite side of its center with a socket 7, which open inwardly toward each other. These sockets are formed, in the present instance, by slitting the member at right angles to a line drawn diametrically thereof and intersecting the slits, and portions of 55 the member without the slits are then

pressed outward as indicated at 8 and 9, the projection 9 and the recess 7 formed thereby being of greater radial depth than the other. The sockets 6 and 7 are of suitable size to receive the ends of the diametrically opposed feet 5 of the fixture stud 4.

In attaching a fixture stud to the terminal member, it is only necessary to first insert a foot 5 thereof into the deeper socket 7 a sufficient depth to enable the opposite foot 5 to be placed in register with the socket 6, after which the stud is moved laterally to cause one foot thereof to enter the socket 6 and the opposite foot to be partially withdrawn from the socket 7, as shown in Fig. 1. The stud is then secured against removal from the member 1 by a screw 10, which in the present instance, is threaded through an opening 11 in the projection 9, and in position for its inner end to have stop contact with the end of the stud foot, which is inserted into the socket 7.

If desired, retaining lips 12 may be struck outwardly from or otherwise suitably formed on the member 1 in position for the other two feet 5 of the terminal stud to be forced thereunder when the stud is moved to force one of the two feet into the socket 6.

Should an exceptionally heavy fixture be 85 used in connection with the stud it might be desired to insert screws through the customary apertures 13 in the stud feet and registering apertures 14 in the member and then into the wall, ceiling or frame work carrying the terminal member 1.

With my invention a fixture stud having the terminal wires projected laterally from its base and connected to the lead-out or terminal wires, which are projected through the "knock-out" openings, may be easily and quickly secured to the terminal member by slipping one foot 5 thereof, to the full extent into the socket 7, which permits the opposite foot to be placed in register with the socket 6, and the other two feet to be 100 placed in register with the recesses formed by the lips 12, after which the stud is moved toward the socket 6 to insert its registering foot therein and to place its other two feet in engagement with the lips 12; the stud 105 being then fixed in this position by the screw 10.

I wish it understood that my invention is not limited to any specific construction, arrangement or form of the parts, as it 110

is capable of numerous modifications and changes without departing from the spirit of the invention as defined in the claims.

Having thus described my invention, what I claim as new, and desire to secure by Letters Patent, is,—

1. An electric outlet box or plate having opposed sockets in its outer side with one of greater depth than the other, and a fixture stud fitting against said side and having opposed feet removably inserted into said sockets and held by the walls thereof to said member.
2. An electric outlet box or plate having opposed inwardly opening sockets in its outer side with one of greater depth than the other, and a fixture stud bearing against said side and having opposed feet removably inserted into said sockets and held by the walls thereof to said member.
3. An electric outlet box or plate having opposed sockets in its outer side with one of greater depth than the other, a fixture stud bearing against said side and having opposed feet removably inserted into said sockets and held by the walls thereof to said member, and means for engaging the stud to prevent its disengagement from said sockets.
4. A terminal member of the class described, having opposed inwardly opening sockets, a fixture stud having opposed feet removably inserted into said sockets and held by the walls thereof to said member, and means projected into one of said sockets and engaging the inserted foot to prevent removal of the stud from the terminal member.
5. A terminal member of the class de-

scribed, having two opposed inwardly opening sockets, a fixture stud having opposed radially projecting feet removably inserted into said sockets, the length from tip to tip of said feet being greater than the distance between said sockets and one socket being deeper than the other to permit the inserted foot to be inserted a greater distance therein to withdraw the other foot from its socket, and releasable means for engaging said stud and preventing removal of its feet from said sockets.

6. A terminal member of the class described, having opposed sockets, a fixture stud having opposed feet removably inserted into said sockets and held by the walls thereof to said member, said stud being removable by lateral movements relative to the member from engagement with said sockets, and lips projecting from the member and engaging with the feet of the stud when the stud is interengaged with the sockets.

7. A terminal member of the class described, having opposed sockets, a fixture stud having opposed feet removably inserted into said sockets and held by the walls thereof to said member, said stud being removable by lateral movements relative to the member from engagement with said sockets, and lips projecting from the member and engaging with the feet of the stud when the stud is interengaged with the sockets, and means for preventing lateral movements of the stud when in engagement with said sockets.

In testimony whereof, I have hereunto signed my name to this specification.

CHARLES N. DETWILER.
